Inventor:

I.S. Sanson

UNITED STATES PATENT OFFICE.

J. S. SANSON, OF PHILADELPHIA, PENNSYLVANIA.

RAILROAD-SWITCH.

Specification of Letters Patent No. 27,009, dated January 31, 1860.

To all whom it may concern:

Be it known that I, J. S. SANSON, of Philadelphia, in the county of Philadelphia and State of Pennsylvania, have invented a new 5 and Improved Railroad-Switch, Designed More Especially for City Railroads; and I do hereby declare that the following is a full, clear, and exact description of the same, reference being had to the annexed drawings, making a part of this specification, in which—

Figure 1, is a plan or top view of my invention. Fig. 2, a plan or top view of ditto, with the bridge and movable platform removed. Fig. 3, a transverse section of Fig. 1, taken in the line x, x . Fig. 4, a transverse section of Fig. 2, taken in the line y, y .

Similar letters of reference indicate corresponding parts in the several figures.

20 The object of this invention is to obtain a simple self-acting switch for city railroads, one that may be actuated by the passage of the horse and car over it so as to coincide, or be adjusted in line, with either the branch or 25 main track as may be desired, no special adjustment being required in any case.

To enable those skilled in the art to fully understand and construct my invention, I will proceed to describe it.

30 A, A, represent the rails of a main track and C, C, the rails of a branch track. At the junction of these two tracks a pit D, is sunk, said pit having a metal bar E, fitted at both ends in its upper part, the bars being 35 flush with the surface of the ground between the rails. These bars E, E, are both recessed at their centers as shown at a, a , to receive the ends of a metal stationary plate F, which I term a bridge, and which is secured to the 40 bars E, by proper bolts or screws b.

The bridge F, is of such a width as to allow plates G, of nearly equal width to be placed one at each side of it. These plates G, G, however are not attached to the bars 45 E, E, but are secured to arms c, c, which are connected to a central rod d, near its ends. The plates G, G, arms c, c, and rod d, may be of cast-iron and all cast in one piece. The ends of the rod d, project sufficiently beyond 50 the arms c, c, to form journals which are fitted in the bars E, E, at their centers and are allowed to turn freely therein. Each plate G, has a flanch e, projecting down from its outer edge. These flanches extend the whole 55 length of the plates G, G. On the upper

edges of the plates G, G, at their outer edges there are flanches f, f', the flanch f, of one plate G, corresponding with one of the rails A, of the main track, and the flanch f', of the other plate corresponding with one of 60 the rails C, of the branch track, as clearly shown in Fig. 1. The flanches f, f', are of taper form and extend only a portion of the length of the plates. At each end of each bar E, there is a vertical ledge or tip g. 65 These ledges or lips are in line with the outer edges of the plates G, G.

Within the pit D, there are placed two levers H, H. These levers are placed transversely in the pit D, and each lever has a 70 weight h, at its inner end. The levers are of bent form and have their fulcrum at i, as shown in Figs. 3 and 4. The upper ends of the levers H, H, project over toward the center of the pit D, and directly underneath 75 the flanches e, of the plates G, G, as shown clearly in Fig. 3. The flanches F, F', of the plates G, G, form guides for the wheels of the car and direct the car on either of the tracks according as said flanches may be adjusted or raised and lowered. In consequence of having the plates G, G, attached by arms c, c, to the rod d, said plates may be tilted and either plate G, with its flanch raised or depressed as may be desired. 80 When it is required for a car to pass on the branch track C, the plate G, having the flanch f', on it is raised by depressing the other plate G, which has the flanch f, on it, and the wheels will be guided on said branch 85 track. When it is required for the car to remain on the main track the plate G, having the flanch f, is elevated by depressing the other plate G, which is provided with the flanch f'. The plates G, may be depressed by any proper means. If one-horse 90 cars be used, the horse may be driven over the plate to be forced down.

The horse may be attached to the car in the usual way the thills being connected to 100 the car by a bolt. If the switch does not require to be operated or is set right for an approaching car, the horse is allowed to pass over the bridge F, but if the switch requires to be operated the horse by a slight pull of 105 either rein is made to pass over either of the plates G as may be desired to move the switch in the proper position. If two-horse cars be used the switch could not be thus operated as the plates are in line or in the 110

paths of the horses and the horses pass over the plates, one over each, and neutralize their action. To a two horse car therefore levers may be attached one at each side, of the driver's platform, either of which levers may be depressed at the right time by the driver in order to press down the proper plate G.

When a plate G, is depressed the lever H, 10 on which its flanch *e*, bears has of course its outer end depressed and the loaded inner end is elevated. These levers H, H, steady the plates G, G, in either position preventing them from casually moving and also preventing 15 them from slamming or descending

too rapidly under the weight that depresses them.

Having thus described my invention what I claim as new and desire to secure by Letters Patent, is—

The tilting plates G, G, provided with the flanches *f*, *f'*, and arranged in relation with the loaded levers H, H, and the rails A, A, C, C, to operate as and for the purpose set forth.

20

J. S. SANSON.
